ATTORNEYS.

UNITED STATES PATENT OFFICE.

EDWARD CLAYTON, OF HALIFAX, NOVA SCOTIA, CANADA.

CLOTHING SAMPLE.

SPECIFICATION forming part of Letters Patent No. 323,113, dated July 28, 1885.

Application filed February 26, 1884. (No model.)

To all whom it may concern:

Be it known that I, EDWARD CLAYTON, of Halifax, in the Province of Nova Scotia, and Dominion of Canada, have invented a new and 5 Improved Clothing Sample, of which the following is a full, clear, and exact description.

The object of my invention is to provide a new and improved clothing sample in which the cloth lining, buttons, pockets, and trimmings in general of the article of clothing can 10 be shown within a very small compass.

The invention consists in a piece or sample of cloth of which the article of clothing is to be made, on which piece samples of the buttons to be used on the garment are fastened, button-holes and pockets formed, trimmings and linings secured, the manner of finishing the lining shown, price and size cards attached, &c., so that every distinctive feature 15 of the garment will be shown on the above-mentioned piece of fabric or the sample.

Reference is to be had to the accompanying drawings, forming part of this specification, in which similar letters of reference indicate corresponding parts in both the figures. 20

Figure 1 is a face view of my improved clothing sample. Fig. 2 is a back view of the same.

On a piece, A, of the cloth or fabric of which 30 the suit or garment is to be made one button, B, of each kind is sewed or otherwise secured, and in the piece A a button-hole, C, is made and finished in the same manner as the button-holes will be finished in the suit or garment. A pocket-slit, D, with or without a flap, D', is also formed in the piece A, and is finished in the same manner as the pockets 35 will be finished in the suit or garment. To the back of the piece A the lining E is sewed, 40 and part of the same is stitched in the manner that the lining is to be stitched in the gar-

ment. A hanger, F, of the kind to be secured on the garment is secured on the piece A. On the piece A are also secured a size-card, H, and price-card G, which cards carry the different 45 sizes, prices, and other necessary information. The sample is very compact; can be sent by mail; it occupies very little space, thus enabling a traveling salesman to carry a large number of patterns and samples which he could not do 50 as well if he would have to take a suit or a garment as sample. The sample-cards also make it very convenient to select a certain kind of cloth, manner of finish, lining, buttons, &c., without requiring the party selecting it to go to the tailor's establishment and without requiring the transportation of entire 55 suits or garments to the customer's house, as everything relating to the suit or garment is shown on the sample. 60

Having thus described my invention, what I claim as new, and desire to secure by Letters Patent, is—

1. A clothing sample consisting of a single piece of cloth on which buttons, lining, a hanger, and price-cards are secured, substantially 65 as herein shown and described.

2. In a clothing sample, the combination, with a single piece of cloth in which a button-hole is made, of buttons, lining, and price card 70 secured on the said piece of cloth, substantially as herein shown and described.

3. In a clothing sample, the combination, with a single piece of cloth in which button-holes and pocket-slits are formed, of buttons, 75 linings, and price-cards secured on the said piece of fabric, substantially as herein shown and described.

EDWARD CLAYTON.
